UNITED STATES PATENT OFFICE

BENJAMIN AKINES, OF JACKSON, MISSISSIPPI

DESIGN FOR A CLOCK CASE

Application filed December 29, 1930. Serial No. 38,150. Term of patent 3½ years.

To all whom it may concern:

Be it known that I, BENJAMIN AKINES, a citizen of the United States of America, residing at Jackson, in the county of Hinds and State of Mississippi, have invented a new, original, and ornamental Design for a Clock Case, of which the following is a specification, reference being had to the accompanying drawings, forming a part thereof.

Figure 1 is a front elevation of a clock case showing my new design,

Figure 2 is a view of one end of the clock,

Figure 3 is a view of the opposite end of the clock, and

Figure 4 is a rear elevation.

I claim:

The ornamental design for a clock case as shown.

BENJAMIN AKINES.
